UNITED STATES PATENT OFFICE.

ALBERT J. MEIER, OF GLENDALE, MISSOURI, ASSIGNEE, BY MESNE ASSIGNMENTS, TO
UNIT CONSTRUCTION COMPANY, A CORPORATION OF DELAWARE.

SYSTEM OF CONSTRUCTING BUILDINGS.

992,739.

Specification of Letters Patent. Patented May 16, 1911.

Application filed July 27, 1909. Serial No. 509,775.

To all whom it may concern:

Be it known that I, ALBERT J. MEIER, a citizen of the United States, residing at Glendale, in the county of St. Louis and 5 State of Missouri, have invented certain new and useful Improvements in Systems of Constructing Buildings, of which the following is a specification, reference being had therein to the accompanying drawings.

10 This invention pertains to a system of constructing buildings, and has for its object to dispense with the use of centering in the construction of concrete or other floors formed of plastic composition.

15 A further object of my invention is to provide a novel type of portable floor or other slab which may be quickly and readily applied in position and which will be capable of withstanding enormous static pressure.

20 By use of the present invention the slabs are constructed as individuals and are allowed to set or harden thoroughly prior to being applied in position. Thus the slabs 25 are virtually independent of each other and when applied in position collectively form the floor, wall, or other bounding surface.

It is a further object of my invention to 30 provide novel means whereby the independent slabs are united to the supporting column so as to collectively form a floor, wall or the like, which is, to all intents and purposes, as though it were a single continuous integral mass.

35 Further and other objects will later herein be manifested and pointed out.

In the drawings, Figure 1 is a top plan view of the floor of a building embodying the present invention, Fig. 2 is a side elevation illustrating some of the slabs applied in position, Fig. 3 is a detail plan view, partly in section, of a column and four of the slabs shown as being affixed thereto, Fig. 4 is a fragmentary sectional view on line 40 4—4 of Fig. 3, Fig. 5 is a similar view taken on the line 5—5 of Fig. 3, and Fig. 6 is a view in perspective of one of the portable slabs.

In the present invention the slabs are

manufactured so as to be portable, and independent of each other, the same after manufacture being suitably secured or affixed to the columns of the building.

Each slab is formed of metal beams designated 1 in the drawings. The beams are 55 preferably of channel-iron, the channel parts of the beams facing inwardly and having a rectangular arrangement. For the purpose of uniting the beams where the same engage each other at their ends, there 60 are angle plates 2, attached to the inner faces of the beams whereby the frame of the slab is held in assembled condition. The flanges 3 of the beams face inwardly, thus leaving the plain sides of the channel frames 65 exposed. As shown in Fig. 6 of the drawings, and as seen in dotted lines in Fig. 3, the angle plates 2 close the space left open at the abutting ends of the channels of the bars or beams 1, and serve to rigidly unite 70 the bars or beams which constitute the frame of a slab. As shown in Fig. 6 the frame formed by the beams is filled with a mass of concrete or other suitable fire-proof flooring material, denoted by the reference numeral 4. 75

For the purpose of properly uniting the beams, which constitute the slab frame, to the columns of the building, bolt holes 6 are formed through the side faces of the beams at each end thereof. The mass or 80 body of the concrete is cut away or omitted at each corner of the frame, as indicated at 8', enabling free access of the hands of the mechanic to properly apply the bolts or rivets in securing the beams of the slabs to 85 the girders. The beams on their top faces, as well as on their bottom faces, are formed at intervals along their lengths with bolt holes 7, for a purpose later set forth. The concrete body 4 is further formed so as to 90 leave a space 7' at points opposite bolt holes 7, the purpose of which, as above stated in connection with the bolt holes 6, being to permit ease and facility in fastening of the frames of the slabs directly to each other. 95

In the drawings there are indicated columns 5 which are arbitrarily depicted as being of square cross section, to which the

slabs are bolted or otherwise rigidly and firmly secured. By reference to Fig. 1, it will be observed that the columns 5, have a rectangular arrangement due to the fact that 5 the slabs themselves are possessed of similar shape, the two ends 9 of the slab frames being of less length than that of the sides 10, the ends 9 being of such length as to span the distance between adjacent faces of the 10 columns against which they abut, while the sides 10 are of such length as to extend from the said faces of the columns to the corresponding faces of the columns at each end of the slab. The sides 10 engage the column 15 and are engaged by the ends 9 of adjoining slabs. Thus it will be obvious that each slab is arranged so that it has contact with the column and with its fellow adjoining slab. The slabs evidently contribute mutual 20 support to one another, since each slab contacts with one or more columns, according to the location of the slabs, and it in turn engages with the adjoining slab.

For the purpose of securely uniting the 25 slabs, plates 8 are fastened to the top and bottom faces of adjoining slabs at their abutting portions, the plates extending from one beam to the adjoining beam of the adjacent slab and are secured by bolts or rivets 30 which extend through the bolt holes 7 previously mentioned, the two channel beams in their assembled relation as shown in Figs. 4 and 5 literally constituting I-beams.

For the purpose of sustaining or supporting 35 the slabs against downward movement a series of elements arbitrarily illustrated as brackets 11 are secured to the columns 5 to afford suitable support to the slabs. The brackets constitute but one of a number of 40 means which can be employed to sustain or support the slabs against downward movement, since the function of the so-called brackets is to provide a rest or footing for the slab. By extending or facing the flanges 45 of the beams inwardly, it will be evident that a firm hold or footing is provided for the concrete mass, since the latter seats or engages with the top and bottom flanges of each of the bars or beams. The slabs may 50 be constructed of any shape and material. The body of plastic material completely fills the space between the beams of the frame and since it is engaged with the top and bottom flanges of the beams, the latter serve 55 to protect the marginal edges of the body of concrete, the beams completely inclosing the body of plastic material at its sides and ends, acting as a metallic protector and strengthener therefor.

60 What is claimed is:—

1. A portable structural slab, comprising a skeleton metallic frame filled in with a body of hardened plastic material, the mem-

bers of said frame having openings formed therein for the reception of fastening devices, portions of said body of material being removed adjacent said openings, to expose the inner faces of the frame members at such points and to afford access to the fastening devices. 65

2. A portable structural slab comprising a quadrangular metallic frame consisting of four load sustaining beams connected together at their ends and having openings in the web portions thereof for the reception 75 of fastening devices, and a body of hardened plastic material filling said frame, portions of said body of material being removed adjacent said openings to afford access to the fastening devices. 70

3. A portable structural slab comprising a skeleton metallic frame composed of load sustaining flanged beams, connected together at their ends and formed with bolt holes, the flanges of said beams being inturned, and a body of hardened plastic material filling said frame and supported by said flanges, portions of said body of material adjacent the bolt holes being removed to afford access to the bolts received in said 85 holes. 90

4. A building construction comprising a column, a series of juxtaposed individual slabs having sides and ends, each slab having a corner thereof abutting the column and an end and side abutting respectively the side and end of the adjacent slabs and connected to the same, the abutting corners of said slabs being secured to said column, and means secured to said column for supporting 100 said corners against downward movement. 95

5. The combination with a series of columns arranged in spaced parallel rows and provided with supports, of a flooring consisting of juxtaposed individual slabs having their 105 corners resting on said supports, each slab extending along one face of each of its supporting columns and terminating flush with the adjacent face of the same. 110

6. In a building construction, the combination, with a series of juxtaposed individual slabs each having a load sustaining metallic frame provided with side and end members the side and end members of the frame of each slab abutting the end and side members respectively, of the frames of adjacent slabs, of a column interposed between the mutually adjoining inner corners of said frames and provided with supports upon which said corners rest, means for fastening together the abutting members of the frames of adjoining slabs, and additional means for anchoring said frame corners to said supports. 115

7. The combination, with a series of individual slabs arranged in the form of a rec- 120

tangle, each slab having sides and ends, the
sides and ends of each slab abutting the
ends and sides, respectively, of the adjacent
slabs, of a column interposed between the
5 mutually-adjoining inner corners of said
slabs and provided with supports upon
which said corners rest.

In testimony whereof I have affixed my
signature in presence of two witnesses.

ALBERT J. MEIER.
